UNITED STATES PATENT OFFICE.

FRANK MARTIN AND MARTIN V. HASKINS, OF WORCESTER, MASSACHUSETTS.

RIDDLE OR SIEVE.

940,338.

Specification of Letters Patent. Patented Nov. 16, 1909.

Application filed March 25, 1908. Serial No. 423,112.

To all whom it may concern:

Be it known that we, FRANK MARTIN and MARTIN V. HASKINS, both citizens of the United States of America, and residents of 5 Worcester, in the county of Worcester and State of Massachusetts, have invented a new and useful Riddle or Sieve, of which the following is a specification.

Our invention relates to improvements in 10 sieves commonly called riddles which are used by molders, and consists essentially of certain peculiar detachable means for holding the foraminous bottom in place, together with means for supporting said bottom in- 15 side of its edges and for strengthening the same, all as hereinafter set forth.

The objects of our invention are, first, to provide a strong, durable, serviceable and comparatively inexpensive device of the 20 class specified, and, second, to furnish such a device with simple but efficient means for securely holding the bottom or sieve proper in place, which means can be easily and quickly manipulated to release the old bot- 25 tom and to fasten a new one in position. We attain these objects by the means illustrated in the accompanying drawings, in which—

Figure 1 is a sectional view of a part of a riddle embodying our invention, such section being taken through the fastening device for the foraminous bottom and the inner ring or binder for such bottom; Fig. 2, a reduced plan view of said bottom with the wire support beneath; Fig. 3, a cross-section 35 on lines 3—3, Fig. 2; Fig. 4, a section through and interior view of a portion of said binder, showing the slip joint formed by the ends or terminals thereof, and, Fig. 5, an isometric view on a reduced scale of 40 said support for the foraminous bottom.

Similar figures refer to similar parts throughout the several views.

Our riddle or sieve comprises an annular rim 1, an internal ring, spreader or binder 2, 45 a foraminous bottom 4, a support 5 for the interior portions of said bottom, a screw 6, and two nuts 7 and 8, which members we will now proceed to describe in detail, also describing their relation to each other.

50 The rim 1 has an external roll or bead 9, with a stiffening wire 10 therein, at the top,

and an internal roll or bead 11, with a similar wire therein, at the base. A groove 12 is formed on the inside of the rim 1 some distance above the bead 11, and below this 55 grooved part the wall of said rim extends inward and then outward to meet said bead, thus forming an inwardly-directed annular ridge 13. An opening 14 is made in the ridge 13 for the screw 6.

The binder 2, which is designed to be placed in the rim 1 below the groove 12 as a medium for firmly securing the bottom 4 in position, has an interior ridge 15 similar to the ridge 13, and is turned inward at the 60 top to form a bead 16. The binder 2 is more or less resilient and so constructed that its ends overlap, and in these overlapping terminals are slots 17—17 which partially or wholly coincide under normal conditions. The slots 17 like the opening 14 are for the screw 6. Four notches 18, two of which appear in Fig. 4, are cut in the upper edge of the binder or in the bead 16 to receive the ends of the support 5, and the 65 inner terminal of said binder is cut away at the top, as shown at 19, to enable such terminal to clear said support.

The bottom 4, which is round and usually made of woven wire, is provided with a 70 downwardly and inwardly extending flange 20 adapted to be received between the upper, inwardly inclined portions of the rim and binder, with the edge 21 of said bottom supported on the bead 16 in the groove 12.

The support 5 is preferably made of cross wires twisted together in the center, with the ends bent downward and inward as shown at 22. This support is placed in the notches 75 18 in the binder 2, under the bottom 4, with 90 the bent ends 22 against the outside of said binder.

Adjacent faces of the nuts 7 and 8 are respectively shaped to fit into the ridge 13 on the outside and to receive the ridge 15 of the 95 inner terminal of the binder, as shown in Fig. 1.

After the parts have been assembled by forcing the bottom 4 into the rim 1 and compressing the binder 2 until it can be introduced into said rim, with the support 5 between said bottom and said binder, the mem-

bers are securely fastened together by means of the screw 6 and the nuts 7 and 8, the slots 17 having first been brought into line with the opening 14 by turning the binder in the 5 rim to whatever extent may be necessary. Before tightening the screw 6 the binder is expanded as much as possible, the slots 17 permitting this to be done. When expanded the binder is not only held in place by the 10 nuts and screw, but is further secured against downward displacement by the coinciding ridges 13 and 15 and the bead 11. The flange 20 and the edge 21 of the bottom are now so securely held between the rim and 15 the binder, owing to the peculiar construction of those portions of these parts which contact with said bottom, that there is no liability that the bottom will become loose, and the bottom is further supported and 20 strengthened by the presence of the member 5. When the old bottom 4 is worn out, or if for any other reason it becomes necessary or desirable to replace it with a new one, all that is required is to loosen the screw 6, compress the binder 2, remove the old bottom, 25 insert a new one, expand said binder, and again tighten said screw. The bottom 4 possesses some degree of flexibility, enough in fact to allow it to be forced into and out 30 of position in the rim.

The support 5 may in some cases be omitted. The nut 7 is usually unthreaded.

Changes of minor importance in details of construction, as well as alterations in shape 35 and size, may be made in our device without departing from the nature of our invention.

What we claim as our invention, and desire to secure by Letters Patent, is—

1. The combination, in a device of the 40 class specified, of a rim having a grooved part to form an interior groove and having an interior ridge which starts from the base of the aforesaid grooved part of said rim and extends downwardly and inwardly and 45 then downwardly and outwardly, a compressible binder inside of such rim and similarly formed to said ridge, a flanged foraminous bottom adapted to be held in said groove by such binder with the flange of said bottom between the downwardly and inwardly extending portions of said binder and rim, and means to fasten the binder and rim together.

2. The combination, in a device of the 55 class specified, of a rim having an interior inwardly directed ridge substantially V-shaped in cross-section, a compressible binder in such rim, such binder having a ridge like the aforesaid ridge of said rim, a flanged 60 foraminous bottom adapted to rest on such binder with its flange between downwardly and inwardly extending portions of said binder and rim, and means to fasten the

binder to the rim, such means passing through and bearing against said ridges at a 65 point in the bends or elbows thereof.

3. The combination, in a device of the class specified, of a perforated rim, a compressible binder having overlapping and slotted terminals in such rim, a flanged foraminous bottom adapted to rest on such binder with its flange between said binder and the adjacent wall of said rim, and means to fasten the binder to the rim, such means comprising a screw passing through the rim 70 perforation and the binder slots and nuts respectively outside of the rim and inside of the binder on said screw.

4. The combination, in a device of the class specified, with a perforated rim having 80 an interior ridge, a compressible binder in such rim, said binder having overlapping and slotted terminals and a ridge similar to that in the rim, the perforation in the rim and the slots in the binder being in the bends 85 or elbows of the ridges, and a flanged foraminous bottom adapted to rest on such binder with its flange between downwardly and inwardly extending portions of said binder and rim, of a screw passing through 90 said perforation and slots, and nuts on said screw capable of closely and firmly embracing the parts of said ridges with which said nuts contact.

5. The combination, in a device of the 95 class specified, of a rim having an interior bead at the base and an interior inwardly-directed ridge above substantially V-shaped in cross-section, a compressible binder in such rim, such binder also being substantially V-shaped in cross-section like the aforesaid ridge of said rim, a flanged foraminous bottom adapted to rest on such binder with its flange between the downwardly and inwardly inclined parts of said binder and 100 rim, and means to fasten the binder to the rim.

6. The combination, in a device of the class specified, of a rim having a groove 110 therein and an interior inwardly-directed ridge substantially V-shaped in cross-section, a compressible binder in such rim, such binder also being substantially V-shaped in cross-section like the aforesaid ridge of said rim, a flanged foraminous bottom adapted to 115 be held in said groove by such binder with the flange of said bottom between the downwardly and inwardly inclined parts of said binder and rim, and detachable means to fasten the binder and rim together.

7. The combination, in a device of the class specified, of a rim having an interior inwardly-directed ridge substantially V-shaped in cross-section, a compressible binder in such rim, such binder also being substantially 125 V-shaped in cross-section like the

aforesaid ridge of said rim, a wire support on such binder, such support consisting of cross wires twisted together at the center and bent downwardly and inwardly at the ends, a foraminous bottom on said support such bottom having a downwardly and inwardly inclined flange, and detachable means to fasten the binder and rim together with the

downwardly and inwardly inclined parts of the support and bottom between corresponding parts of the binder and rim. 10
